UNITED STATES PATENT OFFICE.

CASIMIRO FERRO, OF ANSONIA, CONNECTICUT.

SELF-ATTACHING CURTAIN-BRACKET.

1,325,236.

Specification of Letters Patent. Patented Dec. 16, 1919.

Application filed June 24, 1919. Serial No. 306,344.

To all whom it may concern:

Be it known that I, CASIMIRO FERRO, a citizen of the United States, residing at Ansonia, county of New Haven, State of Connecticut, have invented an Improvement in Self-Attaching Curtain-Brackets, of which the following is a specification.

This invention relates to brackets or hangers, and especially, although by no means exclusively, to brackets for supporting window shades, curtains, portières or other door and window hangings.

The invention has for its object to provide a simple and inexpensive bracket or hanger of such construction as to be self attaching to the wall, door or window frame, or other part by which it is to be supported without the use of nails, screws, or other fasteners, the device being attached or removed by a simple operation without the use of tools, but when in place being securely retained against accidental dislodgment.

The foregoing and other objects of the invention, together with means whereby the same may be carried into effect, will best be understood from the following description of certain forms or embodiments thereof illustrated in the accompanying drawings, in which:

Figure 1 is a face view of a pair of combined shade roller and curtain rod brackets, showing the same in the flat or unbent form in which they are initially produced.

Fig. 2 is a side elevation of one of the brackets illustrated in Fig. 1, showing the same completed and attached.

Fig. 3 is an elevation of a similar bracket showing the same arranged for attachment in a different position.

Fig. 4 is an elevation similar to Fig. 2 of a slightly modified form of bracket arranged similarly to the bracket shown in Fig. 3, illustrating the method of attaching the bracket.

Figs. 5 and 6 are views similar to Fig. 1 showing further modifications.

Referring to Fig. 1, each of the brackets or hangers is composed of resilient sheet metal, a plate of which is cut and shaped to constitute a base portion 10 and an integral supporting portion 11. The base portion 10 comprises, in addition to a flat center, a pair of oppositely extending, upper and lower vertical arms 12 and 13 separated

from the supporting portion 11 by alined longitudinal cuts 14 and 15 the inner ends of which are separated to leave a relatively narrow uncut portion 16 by which the base and supporting portions are integrally connected. The base portion 10 further comprises a second pair of oppositely extending arms 17 and 18 disposed transverse to the arms 12 and 13 between the latter, the arm 18 being cut from the material of the supporting portion 11 and the inner end thereof being disposed between the adjacent ends of the cuts 14 and 15 and being integrally connected with the center of said base portion. The arms 12 and 13 are further formed with integral struck-up attaching projections or prongs having free ends or points which are inwardly turned or directed toward the bases of the arms and toward each other.

The form of the supporting portion 11 is susceptible of wide variation, the same being designed to provide a supporting member suitable for the particular purpose to which the bracket or hanger is to be put. Thus, as shown in Figs. 1, 2, and 3, the supporting portion 11 of each bracket includes an upper arm 21 for supporting a curtain pole 22 and lower arms 23 and 24 for supporting inner and outer shade rollers 25 and 26. As shown in Fig. 6, the curtain pole supporting arm 21 is omitted, and the supporting portion 11 comprises two arms 27 and 28 for supporting shade rollers.

In Fig. 5 is shown a supporting portion 11 comprising a single shade roller supporting arm 29. In all of the figures the invention is shown as embodied in a shade or curtain fixture, but it will be obvious that the same might, by suitably shaping the supporting portion or member, be readily employed for other purposes; for example, as a hanger for supporting pictures or other articles.

The arms 12, 13, 17, and 18 are preferably bent or curved backwardly or inwardly in such a manner that each pair of arms constitutes a bowed spring, the outer ends of which engage the surface of the support to which the device is attached, said springs being transverse to one another and intersecting at the center of the base portion 10, which is integral with both springs and with the supporting portion 11.

The device above described may be read.

ily attached to a wall, window frame, or other supporting structure, without the use of tools or fasteners, by first engaging the upper prongs 19 with the support, as shown in Fig. 4, and thereafter flattening the arms 12 and 13, or springing them outwardly to a certain extent against their resilience, and engaging the lower prongs 20 with said support. Thereafter the resilience of the arms 12 and 13 will tend to draw the inwardly turned prongs 19 and 20 toward one another and cause them to grip between them the substance of the wall or other support, thereby securely retaining said device in position. The above operations are facilitated by curving the arms 12 and 13 adjacent the prongs 19 and 20 to form seats 31 against which the fingers may be pressed to force said prongs into the supporting structure, and by further curving the outer end of the arm 13 to form a finger hold or handle 32 which, after the prongs 19 have been engaged, may be grasped to draw the prongs 20 downwardly into their proper engaging position.

When the arms 12 and 13 are sprung or flattened, as above described, in attaching the device, the arms 17 and 18 will be correspondingly sprung or flattened, and when the device is in place the ends of said arms 17 and 18 will engage the surface of the support with a yielding pressure, thereby laterally bracing the device. Where such lateral bracing action is not required, or for use in situations where space is limited and the transverse arms 17 and 18 would be in the way, said arms 17 and 18 may be omitted, as shown in Fig. 4.

In the formation of the device from a single plate of sheet metal, the supporting portion 11 will, of course, initially occupy a position in the plane of the center of the base portion 10 and in use may be left in this position or may be bent into a plane substantially perpendicular to the plane of said base portion, in accordance with the position in which the device is to be attached, the flexibility of the relatively narrow connecting portion 16 readily permitting such bending. Thus, in Figs. 3 and 4, the device constituting a shade or curtain holder is attached to a window frame 30 within the opening thereof and to the side wall of said opening, the supporting portion 11 being parallel to the surface to which the device is attached, and therefore being left unbent or in the plane of the base portion 10, said supporting portion being suitably offset from said surface by the bowed supporting arms. In Fig. 2, the device is shown as attached to the face of the window frame at one side of the opening, the supporting portion 11 being correspondingly bent to bring the same into a position at right an-

gles to the supporting surface and to the plane of the base portion 10.

Having thus described my invention, I claim:

1. A device of the character described comprising a base portion having upwardly and downwardly extending resilient arms provided with attaching projections and a pair of transversely extending resilient bracing arms, and a supporting portion carried by said base portion. 75

2. A device of the character described comprising a sheet metal plate cut and shaped to form a base portion, a pair of integral transversely disposed bowed springs and a supporting member integral therewith. 80

3. A device of the character described comprising a sheet metal plate cut to form a base portion and an integral supporting portion, said base portion having a pair of oppositely extending arms separated from said supporting portion by alined longitudinal cuts and a second pair of oppositely extending arms disposed transverse to said first named arms between the latter, one of the arms of said second pair being cut from the material of said supporting portion and being connected with the center of said base portion between said cuts. 85

4. A device of the character described comprising a sheet metal plate cut to form a base portion and an integral supporting portion, said base portion having a pair of oppositely extending arms separated from said supporting portion by alined longitudinal cuts and provided with integral attaching prongs and a second pair of oppositely extending arms disposed transverse to said first named arms between the latter, one of the arms of said second pair being cut from the material of said supporting portion and being connected with the center of said base portion between said alined cuts. 95

5. A device of the character described comprising a sheet metal plate cut to form a base portion and an integral supporting portion, said base portion having a pair of oppositely extending arms separated from said supporting portion by alined longitudinal cuts and a second pair of oppositely extending arms disposed transverse to said first named arms between the latter, one of the arms of said second pair being cut from the material of said supporting portion and being connected with the center of said base portion between said cuts, the arms of the two pairs being bent to constitute a pair of intersecting bowed springs, and the ends of one of said springs being provided with integral attaching prongs. 110

In testimony whereof I affix my signature.

CASIMIRO FERRO.
